UNITED STATES PATENT OFFICE.

THOMAS HUMMEL, OF DALLAS, TEXAS.

ELECTRICALLY-OPERATED RAILWAY-CROSSING GATE.

943,352.

Specification of Letters Patent. Patented Dec. 14, 1909.

Application filed March 6, 1909. Serial No. 481,759.

To all whom it may concern:

Be it known that I, THOMAS HUMMEL, a citizen of the United States, residing at Dallas, in the county of Dallas and State of Texas, have invented certain new and useful Improvements in Electrically - Operated Railway-Crossing Gates, of which the following is a specification.

My invention relates to new and useful improvements in railway gates.

The object of the invention is to provide a railway gate to be electrically operated and which may be controlled from a point distant from the gate itself, whose arm, or arms will be lowered by the magnetic energy of an electrical solenoid, and which will be raised automatically, on the opening of the electrical circuit, by counter weights upon the arms.

Another object is the provision of an electrically operated railway gate, which in lowering will automatically ring a signal bell as warning and which will automatically light electric lamps upon the arm while down.

With the above and various other objects in view, the invention has relation to certain novel features of construction and operation, an example of which is described in the following specification, and illustrated in the accompanying drawings, wherein:

Figure 1 is a front elevation of the railway gate, one side with the casting and its bearing which are attached thereto, being broken away to show the mechanism on the inside, Fig. 2 is a side elevation, part of the casing being again broken away to show the interior workings of the apparatus, Fig. 3 is a perspective view of the circuit breaking device, used to break the current in the small solenoid, when the gate is down, and thereby break the circuit containing the electric bell, and Fig. 4 is a diagram of the electrical connections.

In the drawings, the numeral 1, designates the casing within which, the controlling mechanism of the railway gate is placed.

2 is a large, hollow solenoid, which is the main agent in lowering the gate.

3 is an iron core, supported freely in the hollow center of a solenoid, by flexible wire cable, 4. The cable 4 extends around half the circumference of grooved pulley 5 and is securely attached to the rim thereon at a

point 6. The pulley 5 is mounted on a shaft 7 which is supported in bearings 8 upheld by angle irons 9.

10 is a casting of which two are employed, and which extend on each side of the casing 60 and are fixedly mounted upon the shaft 7. The two arms of these castings curve together at one end and between them is securely fastened a long arm 11, which carries the incandescent lamps 12. The weight of 65 the long arm 11 is counterbalanced by weighted portions 13 of the castings 10, the weight being sufficient to return the arm to a vertical position, when the solenoid ceases to hold it down. When the arm 11 is returning to a vertical position, a dash-pot 14 acts as a check upon its velocity, preventing a too rapid return and the consequent shock to the apparatus. Within the dash-pot 14, slides a plunger 15, which is provided with 70 suitable valves for the passage of the glycerin, or other fluid, used in the dash-pot. The plunger 15 is attached to a connecting rod 16 at a point 17 in such a manner that the connecting rod may swing freely about 75 the connecting axes in a direction, longitudinal with the pulley wheel, with which the rod 16 is connected.

18 is a short rod passing through a circular slot 19 in the grooved pulley 5, and 80 capable of adjustment in said circular slot by lock nuts or other suitable means. At one side of the grooved pulley, upon this rod is revolvably mounted a fiber roller 20, and at the other extremity of the same rod 90 is pivotally connected the rod 16. The fiber roller 20 operates the circuit breaking device, a detail of which is shown in perspective in Fig. 3. In this device, carbon contacts 21 are mounted in frames 22, attached 95 to a support 23. Binding posts 24 furnish a means for attaching the wires. Similar carbon contacts 25 are fastened in a frame 26, which is supported by an arm 27. A spring 28 holds the two sets of carbon in 100 contact and a hinge 29 permits the upper set to be lifted by the fiber roller 20, just as the gate reaches its horizontal position, thus breaking the circuit.

30 is a plate or panel of slate or other insulating material which is affixed to the side of the casing. Upon this panel 105 is mounted a small hollow solenoid 31, in which is freely supported an iron core 32, carrying upon its lower extremity a cross-piece 33. 110

When the small solenoid 31 is magnetized by an electric current, the core 32 is drawn up, and the cross piece 33 produces a contact between the points 34 which points are in circuit with the batteries 35 and the electric bell 36. The bell 36 is mounted in a box 37, located on top of the casing and provided with perforated sides to permit the free exit of sound. In Fig. 1 this box is shown with the front sides removed to show the bell.

In the diagram shown in Fig. 4 38 designates a switch to be placed in the watch tower or other convenient place. When this switch is closed, current from the lighting mains or from any convenient source passes through the circuit, magnetizing the large solenoid 2, and thereby drawing down the iron core 3 and lowering the gate. Reference now more particularly to Fig. 4, it is to be noted that the lamps 12 are not lighted until the gate is down, since the two sets of carbons 21 and 25 are not separated until then, and the current takes the path of least resistance through the small solenoid and circuit breaker while the latter is closed. Until the gate is down and the circuit breaks open the small solenoid 31 is magnetized, thus closing the bell circuit and ringing the bell. The fiber roller 20 is so situated upon the side of the grooved pulley that just as the arm reaches a horizontal position, this roller rises beneath the frame 26 of the circuit breaker, lifting the carbon contact 25 and thus breaking the circuit. The small solenoid is then demagnetized, the core is released and the contact between the points 34 is broken. Thus the bell rings only when the arm is being lowered. When the switch 38 is open the core of the large solenoid 2 is released, permitting the arms to be brought to a vertical position again by the weighted portions 13 of the castings 10.

What I claim, is:

1. In a device of the character described, the combination with rotatable arms, of a shaft to which said arms are attached, a pulley upon said shaft, an iron core suspended from the rim of said pulley and actuating the same by its motion and a solenoid within which said core is suspended and which actuates said core.

2. In a device of a character described, the combination with rotatable arms, of shafts upon which said arms are mounted, a grooved pulley mounted on one of said shafts and rotating therewith, a rope or cable suspended from the groove of said pulley, and transmitting motion to it, and a metal core suspended from said rope or cable and transmitting motion to it, a solenoid within which said metal core is suspended and which actuates the same, means for counter balancing the weight of said arms and returning them to an upright po-

sition, and means for checking the velocity of the arms and regaining their vertical positions.

3. In a device of the character described, the combination with rotatably mounted arms, of rotatable means upon which said shafts are mounted, means for transmitting the rotation of such means, from one rotating member to another, a hollow electrical solenoid and means for lowering said arms and closing the gate, weights to counter balance the weight of said arms and return them to an upright position, a dash-pot, to check the velocity with which the arms regain their upright position, a circuit breaking device to be opened by the rotation of a rotating member as the arms reach a horizontal position, a small solenoid, connected in series with said circuit breaker and having a freely suspended core by the motion of which two points may be electrically connected, an electrical circuit, containing a bell and batteries, whose circuit is broken at said two points and a circuit containing lights in parallel with the circuit containing the circuit breaker and the small solenoid, said lamps having a higher resistance than said small solenoid.

4. In a railway crossing gate, the combination with rotatably mounted arms, of shafts upon which said arms are mounted, a pulley mounted on one of said shafts, rotating therewith, an electrical solenoid, which on closing the circuit in which it is placed causes said arms to rotate from an upright to a horizontal position, a metal core suspended within said hollow solenoid, and vertically actuated by the same, means for suspending said metal core from said pulley, by which means said pulley may be rotated, a dash-pot whereby the velocity of the ascending arms is restricted, means for connecting said dash pot to said pulley, restricting the velocity with which the same rotates, means for returning the arm automatically from a horizontal to a vertical position, a circuit breaking device in series with a small solenoid which cuts out said solenoid as the arm reaches a horizontal position, means attached to a rotating member whereby said circuit breaking device is operated, an electric circuit including a bell and batteries, which circuit is open or closed by the action of said small solenoid, means for applying the energy of said small solenoid to the opening or closing of said circuit containing bell and battery, and a circuit containing electric lights in parallel with said circuit containing the said circuit breaking device and the small solenoid and of greater resistance than that circuit.

5. In an electrically operated railway gate, a solenoid magnet whereby the gate is lowered, a counter weight to return the gate to a vertical position, an electrical cir-

cuit, including a source of electromotive force, a switch, a light and said solenoid, a shunt circuit in parallel with said light, containing a circuit breaker, adapted to be 5 mechanically opened when the gate is down, and containing an automatic switch whereby a third circuit is closed when the shunt circuit is electrified, and a third circuit, containing an electric bell and source of elec-

tro-motive force, whose source is normally 10 broken by said automatic switch.

In testimony whereof I have signed my name to this specification in the presence of two subscribing witnesses.

THOMAS HUMMEL.
